ATTORNEY.

UNITED STATES PATENT OFFICE

2,612,684

HAIR TRIMMING TYPE RAZOR

Warren M. Mansfield, Glendale, Calif., assignor,
by mesne assignments, to Cutter Corporation,
a corporation of Delaware

Application March 12, 1948, Serial No. 14,613

3 Claims. (Cl. 30—31)

1

The invention relates to a hair trimming type razor and more particularly to an improved form of razor adapted to be used for trimming the hair, thinning the hair, or shaving.

An object of the invention is to provide a device of the character described, wherein the razor blade is adjustable transversely with respect to the contour of the guard, for the purposes described.

For further details of the invention reference may be made to the drawings wherein

Fig. 1 is a side view, in full scale, of a hair trimming type razor according to the present invention.

Fig. 2 is an end view of the razor of Fig. 1.

Fig. 3 is a top plan view of the razor in Figs. 1 and 2.

Fig. 4 is an enlarged sectional view on line 4—4 of Fig. 3 looking in the direction of the arrows, showing the razor blade in hair trimming position.

Fig. 5 is an enlarged view corresponding to Fig. 4, with parts broken away, showing the blade in shaving position.

Fig. 6 is an enlarged sectional view on line 6—6 of Fig. 3 looking in the direction of the arrows.

Referring in detail to the drawings, the hair trimming type razor 1 comprises a guard member 2 and an adjustable blade holder 3 for a double edge flexible razor blade indicated at 4.

The guard member 2 comprises two parallel rows 5 and 6 of spaced guard members each of which has a longitudinal tip as shown at 7 and 8 in Fig. 4 extending generally in the direction of the blade 4. Each tip like 7 in the guard 5 has a straight face 9 which extends transversely of the cutting edge 20 of the blade, all of the faces like 9 in the guard 5 lying in a plane while similar faces 10 on the other guard 6 lie in another plane, these two planes being parallel to each other and spaced apart a distance slightly greater than the distance between the cutting edges 20 and 21 of the blade.

The contour 11 of all the guard members like 7 in the guard 5 and the contour 12 of the guard members like 8 in the guard 6 are intersected at a slight angle by the plane of its associated cutting edge of the blade 4 as will be more readily apparent from Fig. 5. In Fig. 5 it is readily seen that the contour 11 is at a steeper angle than the contour of the plane of the cutting edge 20, also the contour 12 is at a steeper angle than the plane of the cutting edge 21. The contour 11 is intersected by the transverse faces like 9, whereby each guard member like 7 has a transverse tip like 13, the guards like 8 each having a similar transverse tip 14.

2

The guard member 2 has a flat end 15 from which the guard members 5 and 6 arise, the flat end 15 serving as a stop for the flat underside 16 of the inner member 17 of the blade holder 3 which has an outer member 18. The members 17 and 18 have companion curved faces 30 and 31 to hold and clamp the blade 4 therebetween with transverse curvature as shown in Fig. 5.

The blade holder members 17 and 18 are removably held together, with the blade 4 therebetween so that these members can be taken apart to replace a used blade with a new one. For this purpose, the member 18 has a sleeve 32 which fits in the bore 33 in an inner tubular member 34 which fits inside of and concentric with a comparatively short outer tubular member 35 which is integral with the guards 5 and 6. Inside of and along the axis of the inner tubular member 34 is a brass rod 36 having screw threads 37 to engage internal threads 39 in the brass sleeve insert 132 molded in the sleeve 32.

The outer end of rod 36 has a knob 40 and the outer end 41 of the inner tubular member 34 serves as a stop for knob 40. When knob 40 is screwed in, this clamps the blade holder members 17 and 18 together and when it is unscrewed, the blade holder member 18 can be removed. Adjacent the guard end of the outer tubular member 35, the latter is provided with an enlarged bore 42 for a compression spring 43 which bears at one end against a shoulder 44 at the end of bore 42, and at its other end against the lower face 46 of the blade holder member 17, to urge the blade holder 3 outwardly with respect to the axis of rod 36 and tubular members 34 and 35, and outwardly with respect to the faces 9 and 10, towards or beyond the transverse tips 13 and 14. The action of spring 43 is adjustably restrained by brass nut 45 which bears against the lower end 46 of tubular extension 35 acting as a stop, nut 45 having threaded engagement 47 with the outside of brass sleeve 147 molded in the inner tubular member 34 on the portion 48 thereof which extends beyond the end 46 of the outer tubular member 35. The inside of sleeve 147 is broached or roughened to keep it from turning. By adjusting the nut 45, the blade holder 3 with its members 17 and 18 and with blade 4 clamped therebetween, is moved in and out along the transverse faces 9 and 10. During this time, the blade 4 moves parallel to itself while remaining clamped with transverse curvature.

The blade holder members 17 and 18 are properly aligned with each other and with the blade by means of a pair of spaced pins 50 and 51 as shown in Figs. 3 and 6 on the outer holder member 18, such pins passing through apertures like

52 and 53 respectively in the blade 4 and through apertures like 54 as shown in Fig. 6 in the inner blade holder member 17. The pins 50 and 51 also pass through apertures like 55 in the guard 2 in order to locate blade holder 3 and the cutting edges 20 and 21 of the blade with respect to the guards 5 and 6.

Guard 5 is used for trimming, whereas guard 6 is used for thinning. As shown in Figs. 3 and 4, all of the members in the guard 5 have long slots 60 having inner ends which are crossed or intersected by the cutting edge 20 of the blade. On the other hand, the alternate slots like 61 in the other guard 6 are comparatively short and are not intersected by the cutting edge 21 whereby, when thinning the hair, whatever hair falls into the short slots 61 is not cut by the blade.

When using the device for shaving, the nut 45 is operated to elevate the blade 4 to the position shown in Fig. 5 with the cutting edges of the blade a slight distance above the contours 11 and 12 of the guard. When the device is used for trimming the hair, the hair remaining on the skin after cutting is shorter, the more the blade 4 is elevated with respect to the guard 2. A short haircut is obtained when the blade is near the tips 13 and 14, while a long haircut is obtained if the blade is in its lowermost position. The length of haircut can be varied by adjusting the blade with respect to the guard tips 13 and 14. The cuttings can be blown from the device by moving the blade holder 3 to an elevated position beyond that shown in Fig. 5, this being accomplished by operating the nut 45.

The blade holder members 17 and 18 and guard 2 may be molded in plastic material.

The short outer tubular member 35 and the inner tubular extension 48 serve as a handle for the device.

It will be apparent that various modifications may be made in the invention without departing from the spirit of the following claims.

I claim:

1. A hair trimming type razor comprising a curved companion razor blade holders for clamping a double edge razor blade in curved position, a guard for each of the two cutting edges of the blade, each of said guards comprising a plurality of spaced members having tips extending lengthwise in the general direction of the blade, each of said members having a straight face extending transversely of the blade and terminating in transverse tips, said faces of the members of one of said guards respectively lying in a plane, said faces of the members of the other of said guards lying in a plane parallel to said first plane, said planes being spaced apart for close proximity with said cutting edges, the outer contour of the members of each guard intersecting its said plane and being inclined to intersect the associated cutting edge of the blade at a slight angle which is steeper than the plane of the cutting edge of the blade, means supporting said blade holder for movement lengthwise of said transverse tips between (a) a shaving position with each cutting edge of the blade slightly above the contour of its associated guard and (b) progressively longer hair trimming positions along said planes, respectively, inwardly of said shaving position, and

means for securing said blade holder in adjusted position.

2. A hair trimming type razor comprising a blade holder having opposed members for clamping the blade therebetween, a guard having transverse tips having faces respectively lying in a plane transverse to the blade, said guard having teeth having long slots in position to be intersected by the cutting edge of the blade and having alternate short slots out of range of the cutting edge of the blade, said short slots having bottom portions in front of said plane and guarding the cutting edge of the blade for all positions of adjustment of the cutting edge along said plane, means supporting said blade holder for movement of the blade parallel to itself lengthwise of and adjacent said faces of said transverse tips, said means supporting said blade holder for movement of the blade to a shaving position with the cutting edge of the blade adjacent the outer end of said faces, said means supporting said blade holder for movement of the blade to a non-shaving and hair cutting position with the cutting edge of the blade inwardly of said shaving position behind said faces and removed from the outer contour of said tips by an amount which increases as the cutting edge is adjusted inwardly of said faces, and means for securing said blade holder in adjusted position.

3. A hair trimming type razor comprising a blade holder having opposed curved members for clamping the blade in curved position therebetween, a guard having transverse tips, having an outer inclined contour and having faces respectively lying in a plane transverse to the blade, means supporting said blade holder for movement of the blade parallel to itself lengthwise of and in close proximity with said faces of said transverse tips, said means supporting said blade holder for movement of the blade to a shaving position with the cutting edge of the blade adjacent the outer end of said faces, said means supporting said blade holder for movement of the blade to a non-shaving and hair cutting position with the cutting edge of the blade inwardly of said shaving position behind said faces and removed from the outer contour of said tips by an amount which increases as the cutting edge is adjusted inwardly of said faces.
